UNITED STATES PATENT OFFICE.

CARL E. ANDERSON, OF BROCKTON, MASSACHUSETTS.

GAS-GENERATING BURNER.

Application filed February 13, 1925. Serial No. 8,861.

My present invention relates to oil burning systems and particularly to a vaporizing burner for such a system. My burner is of that general type which includes a vaporizing tube or member disposed in the area of combustion so as to be heated to vaporize the fuel in the usual manner.

One of the difficulties experienced with burners of this type has been their tendency to be unsteady in their supply of gas to the burner, or to otherwise cause the flame to flutter. This not only involves a danger of extinction, but is unsatisfactory both from the view-point of economy as well as being an annoyance and cause of worriment, which is particularly unfortunate where such burners are used in cooking ranges. The object of my invention is to prevent this tendency and to otherwise improve the performance of this type of burner.

As illustrative of my invention I have shown a burner of simple and generally standard type which can be constructed, after the commonly accepted fashion of these burners, of simple piping which renders them inexpensive to build and easy to take apart for cleaning or for replacement of parts. Throughout the specification and drawings like reference characters are employed to indicate corresponding parts, and in the drawings:

Fig. 1 is a general view of such an installation partly sectioned to expose a burner in an indicated range.

Fig. 2 is a side view, partly in section, of such a burner.

Fig. 3 is a sectional view of the baffle plate on line $x-x$ of Fig. 2.

Fig. 4 is an enlarged view of a burner nozzle.

I have indicated at 1 a burner base which is adapted to be mounted in the fire box of the heating plant which is indicated generally at 2, and in these drawings is shown as a cooking range of conventional type.

Mounted vertically on the base 1, at one end thereof, is an atomizer unit indicated generally at 3 and as here shown consisting of a pipe having below the base 1 superposed air and oil inlets, indicated at 4 and 5 respectively in Fig. 2. The air inlet is connected by a pipe 6 with a pressure tank 7 which is provided with means here shown as a hand pump 8 for building up a pressure within said tank. The fuel inlet 5 is con-

nected with any suitable supply source, as a pressure tank or the like.

Mounted within the pipe 3 and spaced from the walls thereof is an oil delivering nozzle communicating, at its lower end, with the fuel inlet 5 and having the usual restricted discharge orifice at its upper end. The air intake, therefore, surrounds the nozzle 9 and acts to atomize the fuel discharged from said nozzle. The atomized fuel delivers into a tubular vaporizer including an upwardly inclined section 11 which is coupled at 12 to the upper end of the pipe 3, and at its opposite end is coupled at 13 to a downwardly and horizontally bent burner pipe 14 which is closed at its inner end, as indicated at 15, and is provided between its ends with a plurality of removable and replaceable burner nipples 16. By inclining the section 11 of the vaporizer upwardly from its intake towards its discharge end, the tendency of the flame to flutter, due to fluctuations in the vapor supply, is largely reduced.

In order to effectively distribute the heat from the flame vents of the burner nipple to the overlying inclined vaporizer section 11, I mount on said section a baffle 17 having an extended horizontal baffling area 18 at its lower and at its upper end, provided with a hook 19 which is inclined at an angle corresponding to the angle of inclination of the section 11, whereby said baffle may be moved longitudinally of and angularly adjusted or rotated in a plane transverse to said section 11. Where the burner pipe 14 is provided with more than one nipple 16 I may suspend, from the overlying vaporizer section 11, a baffle plate for each burner nipple.

By providing the burner section 14 with a plurality of vent receiving openings, I am able to make my burner interchangeable so that it may operate with a single vent or a single pair of vents or with a plurality of pairs of vents. Where only a single vent or a single pair of vents is employed, I seal up the remainder of the vent receiving openings with unperforated vent nipples 16 which are provided for that purpose, as is shown in Fig. 4. This makes my burner readily adaptable to different styles of ranges and stoves and also to different grades or qualities of fuel.

These and various other modifications in

the construction and assembly of my oil burner involved, may obviously be resorted to within the spirit and scope of my invention, as defined by the appended claims.

5. What I therefore claim and desire to secure by Letters Patent is:

1. In an oil burner a tubular vaporizer including an upwardly inclined section disposed transversely of the flame vent, an oil and air intake, and a baffle plate having a main baffle portion for deflecting the flame, said main deflecting portion normally assuming a horizontal plane and a supporting hook inclined relative to the main deflecting plate of the baffle at the angle of said vaporizing section and movable longitudinally of and angularly adjustable in a transverse plane relative to said vaporizing section.

15. 2. A self-contained oil burner unit com-

prising a base, having a flange extending 20 upward from the perimeter thereof forming a basin, and an upwardly extending sleeve at one end of the base forming an aperture therethrough, a tubular vaporizer including an upwardly inclined section disposed transversely of the flame vent, an upwardly extending oil intake nozzle and a surrounding air intake pipe in atomizing relation thereto, said intake pipe being supported in the sleeve and being vertically adjustable therein, said inclined section being coupled to the upper end of said air intake pipe, and a burner disposed beneath said vaporizing section whereby said oil burner may be inserted as a self-contained heating unit in a 30 stove.

35. In testimony whereof I affix my signature.

CARL E. ANDERSON.
